UNITED STATES PATENT OFFICE.

LOUIS J. MUELLER, JR., OF MILWAUKEE, WISCONSIN.

COMBINED GARBAGE-BURNER AND HEATER.

1,308,989.

Specification of Letters Patent.

Patented July 8, 1919.

Application filed August 26, 1918. Serial No. 251,455.

To all whom it may concern:

Be it known that I, LOUIS J. MUELLER, Jr., a citizen of the United States, and resident of Milwaukee, in the county of 5 Milwaukee and State of Wisconsin, have invented new and useful Improvements in Combined Garbage-Burners and Heaters, of which the following is a description, reference being had to the accompanying drawings, which are a part of this specification.

10 This invention relates to improvements in garbage burner and water heater.

In many modern homes it is the present practice to burn garbage and other refuse 15 on the premises by means of burners of various kinds. In order to properly burn garbage in the most efficient manner it is necessary to completely dry or eliminate the moisture from the garbage before burning.

20 In burning garbage and other waste material it is very desirable to utilize the heat generated from the burning material to heat water for culinary and other household uses.

It is one of the objects of the present invention to provide a garbage burner and water heater which will perform the before-mentioned desirable functions in a highly 25 efficient manner and which possesses other desirable features which will be later described.

30 A further object of the invention is to provide a garbage burner and water heater having a water cooled grate for supporting the garbage while drying and being consumed thereby performing the two fold function of preventing the burning of the grate, and heating the water which passes through the grate for household use.

35 A further object of the invention is to provide a garbage burner and water heater having means for directing the hot flame and gases from the fuel proper of the heater around all parts of the garbage to thoroughly dry the same preliminary to burning the material.

40 A further object of the invention is to provide a garbage burner and water heater having a novel form of flue construction which carries smoke from the fuel proper 45 to the rear and over the top of the garbage while the garbage is being dried.

50 A further object of the invention is to provide a garbage burner and water heater having a novel means for controlling the 55 dampers or valves of the burner and heater.

A further object of the invention is to provide a garbage burner and water heater having a water cooled grate so constructed as to permit the convenient cleaning of the water flues of the grate. 60

A further object of the invention is to provide a garbage burner and water heater in which the parts are in the form of sections which may be easily assembled together to form the complete structure or 65 taken apart for repairs.

With the above and other objects in view the invention consists of the improved garbage burner and water heater and its parts and combinations as set forth in the claims, 70 and all equivalents thereof.

In the accompanying drawings in which the same reference characters indicate the same parts in all of the views:

Figure 1 is a side view, partly in section, of the improved garbage burner and water heater; 75

Fig. 2 is a vertical sectional view taken on line 2—2 of Fig. 1;

Fig. 3 is an outer side view, on a larger 80 scale, of the upper portion of the garbage burner and water heater;

Fig. 4 is a top view of a modified form of garbage holding grate portion, parts shown 85 in section; and

Fig. 5 is a sectional detail view thereof taken on line 5—5 of Fig. 4.

Referring to the drawings the numeral 8 indicates the base or ash pit section, 9 the fuel burner and water heater section and 10 90 the garbage chamber section.

The base section is of circular form in cross section and tapers slightly downwardly to a larger diameter to form a more firm support. The base section is provided 95 with the usual door 11 for removing ashes from said section and with a draft door 12 for supplying air to the burner. An annular opening 13 is formed in the upper end portion of the base section to receive the annular lower flange 14 of the fuel burner section 9 and hold and support said burner section on the base section. Said burner section 9 is formed with an inner and an outer wall 15 and 15' spaced apart to form 100

an annular water chamber 17 which surrounds the chamber in which the fuel is burned. The inner and outer walls 15 and 15' are connected together at their lower ends and the lower portion of the section is 105 110

provided with a fuel grate 18 for supporting the fuel for drying the garbage. The upper end portion of the burner section forms a garbage holding grate 19 and comprises 5 transversely extending tubular grate bars 20 which are connected to the opposite sides of the burner section and are in communication with the water chamber 17 so that water is free to flow therethrough. The said tubular bars are of rectangular shape in cross section and are spaced sufficiently close to support the garbage and at the same time provide sufficient space between the bars for the passage of the hot gases to dry the garbage.

The section 9 has a charging opening 21 and an extension passage 22 in communication therewith and carrying a door 23, the fuel being introduced in the chamber 20 through the passage 22 and opening 21. For the purpose of cleaning the grate a passage 24 is formed in the section 9 and an extension passage 25 is secured to said section and carries a door 26 whereby access may be had 25 to the grate 18.

In Figs. 4 and 5 of the drawing I have shown a modified form of water grate for supporting the garbage consisting of a concentrically disposed annular tubular portion 27 in communication with the upper portion of the chamber 17 through radial passages 28 and a diametrically extending channel 29 in line with some of the radial passages 28.

35 In either construction the water to be heated is introduced into the chamber 17 and grate through one of the openings 30, the other opening being closed by a plug 31 and is carried away through one of the openings 40 32, the other opening being closed by a plug (not shown). The upper openings 30 are so located with respect to the hollow grate sections as to permit of the introduction of a cleaning tool or device to remove boiler 45 scale collecting in the tubes of the grate.

The garbage section 10 has a conical wall 34 with an annular recessed lower edge 35 and flange 36 resting upon the top of the section 9 and secured thereto by bolts 37. The wall 34 has a side opening 38 through which 50 garbage is introduced upon the grate, which opening is normally covered by an outwardly and downwardly swinging door 39. The section 10 has a closed top portion 40 55 provided with a centrally disposed flanged outlet 41 and a flue 42 which communicates with the upper portion of the garbage chamber through an opening 43 in the wall 34 and at its lower end communicates with the upper portion of the combustion chamber below the garbage grate through an elbow pipe fitting 44 and an outlet passage 45 in the upper portion of the section 9.

To provide for efficient drying of the garbage upon the grate radially disposed in-

wardly extending ribs 46 are secured to the interior of the wall 43 and forming channels to permit the products of combustion to pass through the garbage and prevent packing down of the garbage around the rim of the 70 grate.

The inlet 47 to the flue 42 is provided with a damper valve 49 and the outlet 41 is provided with a damper 48 and means are provided for simultaneously moving the valves 48 and 49 consisting of a lever 50 pivotally connected to one arm of a bell crank lever 51 pivotally mounted on the section 10 and a link 52 pivotally connected to the other arm of lever 51, and means for operatively connecting the lever 50 with the valve 48 and the link 52 with the valve 49. The valve 48 is provided with a rod 53 having a cranked end 54 which is slidably mounted in an arc-shaped slot 55 in the lever 50 so that a back and forth movement of the lever 50 will cause a turning of the rod 53 and the valve 48. The valve 49 is provided with a rod 56 having a cranked end 57 which is slidably mounted in a slot 58 in the link 52 so that an up and down movement of said link through a swinging of the lever 51 by the lever 50 will turn said rod 56 and the valve 49. To secure the valves in different positions of adjustment the lever 50 is provided with notches 50' adapted to be brought into locking engagement with a guide bracket 59 mounted on a lug 60 on the section 10. With this construction the valve 49 is closed when the valve 48 is in about half open position and when the lever 50 is moved to bring the valve 48 in full open position the valve 49 is in full open position as shown in Fig. 1.

With this construction a fire on the grate 18 insures a constant supply of hot water and the garbage is first dried on the garbage supporting grate and then consumed, the burnt garbage being free to fall through the grate into the fire below. In drying the garbage the valve 49 may be shut off so that the products of combustion from the fire on the grate pass up through the garbage on the grate 20 or the valves 48 and 49 may be opened so that the products of combustion pass upwardly through the garbage 115 and also through the flue 42 and over the top of the garbage and out the outlet 41. The device thus serves as an efficient water heater and garbage consumer and the garbage is utilized as fuel to heat the water.

120 What I claim as my invention is:

1. In a combined garbage burner and water heater, the combination of a water heater comprising a combustion chamber provided with an outlet, an annular water chamber surrounding the combustion chamber, a top water chamber cast integral with the annular water chamber and consisting of spaced channels, said top water chamber forming a garbage supporting grate, a gar- 130

- bage section disposed above the grate and provided with an inlet and an outlet, a flue connecting the outlet of said combustion chamber and the inlet of said garbage section, and means in said flue and the outlet of said garbage section for controlling the passage of waste products of combustion from said garbage section and combustion chamber.
2. In a combined garbage burner and water heater, the combination of a water heater comprising a combustion chamber provided with an outlet, an annular water chamber surrounding the combustion chamber, a top water chamber extending across the top of said combustion chamber and consisting of spaced channels, said top water chamber forming a garbage supporting grate, a garbage section disposed above the grate and provided with a plurality of radially disposed inwardly extending ribs, a flue communicating with said garbage section near its top and with said combustion chamber near its top, said garbage section being provided with an outlet, and means for controlling the passage of waste prod-

ucts of combustion through said flue and said outlet.

3. The combination with a combined garbage burner and water heater, including a combustion chamber, a garbage section, a flue communicating with said combustion chamber and garbage section and an outlet from said garbage section, of means disposed in said outlet and said flue for controlling the passage of the waste products of combustion therethrough, means for simultaneously operating the said controlling means and comprising a slidably mounted lever, a bell crank having one arm pivoted to one end of said lever, said lever having means intermediate its ends for engaging the controlling means of said outlet, a link having one end pivoted to the other arm of said bell crank and its other end operatively engaged with the controlling means of said flue, and means engageable with said lever for retaining the same in adjusted position substantially as described.

In testimony whereof I affix my signature.

LOUIS J. MUELLER, JR.
